HOLE LAPPING MACHINE

Alden M. Drake, West Hartford, Conn., assignor to Niles-Bement-Pond Company, West Hartford, Conn., a corporation of New Jersey

Application January 29, 1944, Serial No. 520,257

6 Claims. (Cl. 51—92)

1

This invention relates to lapping machines and particularly to a machine for lapping internal cylindrical surfaces to precision dimensions.

An object of the invention is to provide a machine for automatically reciprocating a work piece having an internal surface to be lapped over the surface of a lapping tool which may be rotated simultaneously with the reciprocations of the work piece.

Another object of the invention is to provide a holder for the work piece being lapped which will allow the work piece to fit freely over the lapping surface of the tool and adjust itself thereon in any direction during the lapping operation.

Another object of the invention is to provide the work holder with means indicating the effectiveness or amount of lapping being done on the work piece during the lapping operation.

And finally it is an object of the invention to provide impact means manually applied under controllable conditions to slightly increase the diameter of the lapping tool during the lapping operation.

With the above and other objects in view the invention includes the features of construction and operation set forth in the following specification and illustrated in the accompanying drawings.

In the accompanying drawings annexed here-to and forming a part of this specification, I have shown the invention embodied in a hole lapping machine for annularly grooved rolls of small size but it will be understood that the invention can be otherwise embodied and that the drawings are not to be construed as defining or limiting the scope of the invention, the claims appended to this specification being relied upon for that purpose.

In the drawings:

Figure 1 is a vertical sectional view through the principal parts of a machine embodying one form of the present invention.

Fig. 2 is a front elevation, partly in section, of some of the principal parts of the machine shown in Fig. 1.

Fig. 3 is a sectional view in elevation showing the impact means for forcing the lap axially along its arbor to adjust the size of the lapping surface during the lapping operation.

Fig. 4 is a detail view of parts shown in Fig. 3 taken from below.

Fig. 5 is a plan view of a form of holder for the work pieces being lapped, and

Fig. 6 is a central sectional view in elevation taken on the plane of line 5—5 of Fig. 5.

2

In the above mentioned drawings there has been shown but one embodiment of the invention which is now deemed preferable, but it is to be understood that changes and modifications 5 may be made within the scope of the appended claims without departing from the spirit of the invention.

In lapping holes in rolls for screw thread gages by means of which they are supported in the gage 10 frame it is essential that the holes be of uniform diameter from end to end and without taper or bell-mouthing. The rolls must fit their arbors closely and from end to end so that the rolls will not tilt on their arbors but will rotate smoothly 15 on a fixed axis. Heretofore precision lapping of internal cylindrical holes has been done manually, the work piece being held manually in position upon a rotating lapping tool and slowly reciprocated back and forth. The lap usually comprised a split cast iron sleeve fitted over a slightly tapered arbor. To expand the lapping surface of the lap the sleeve was forced axially along the tapered arbor.

The present invention provides mechanical 25 means to reciprocate the work piece over the lap during rotation thereof and a novel holder or mounting means to hold the work piece in a manner to permit the work piece to adjust itself upon the lapping surface. Also means are provided 30 for forcing the expandable lap predetermined slight amounts axially during the lapping operation to slightly increase its diameter.

Briefly and in its preferred aspect the invention may include the following principal parts: 35 First, a spindle adapted to be rotated by any appropriate means and having means at its forward end to support a lapping tool extending axially from the spindle; second, a reciprocable member adjacent the rotatably mounted spindle, 40 there preferably being hydraulic or other form of operating means to reciprocate this member and also to vary the speed and distance of travel of this member; third, a work supporting member mounted on and actuated by this reciprocable 45 member permitting adjustment of the work piece in any direction upon the lapping surface; fourth, a plunger aligned with the lapping spindle and adapted to be resiliently retracted and forced forward to engage the lapping tool so that the 50 position of the lapping tool on its spindle may be adjusted axially to slightly increase its diameter.

Referring more in detail to the figures of the drawing and first to Fig. 1, I provide a spindle 55 adapted to be driven by a bevel gear 11 on a short shaft 12 in alignment with the spindle 10

and which in turn may be driven through any suitable connections such as a driving bevel gear 13 connected by means not shown to a suitable source of power. To conveniently start and stop rotation of the spindle 10 a friction clutch 14 may be provided between the spindle 10 and the driving shaft 12. This clutch 14, as shown, may be maintained with its members normally in engaged or driving positions by a spring 15. To disengage the members forming the clutch 14 to stop operation of the spindle 10 a vertically supported shaft 16 having an eccentric projection at its upper end may be rotated by a hand wheel 17 and connections to engage a flange on one of the clutch members.

The forward end of the spindle 10 is provided with a chuck 18 within which may be mounted a lapping tool arbor 19. As this chuck 18 may be of any suitable form permitting quick and convenient change of lapping tool arbors, it is not thought that further description will be needed. It will suffice to state that the lapping tool comprises an arbor 19 having a slightly tapered surface over which is fitted an expansible lapping member 20 preferably in the form of an elongated sleeve slotted along one side as shown, the outer surface of this member being cylindrical. By adjustment of this member 20 axially along its tapered arbor 19 the diameter of its outer cylindrical surface may be slightly varied during the lapping operation.

In order to adjust the position of the lapping member 20 upon its arbor 19 as required during the lapping operation, impact means are provided which may be actuated manually to deliver a carefully regulated blow upon the end face of the split sleeve forming lapping tool 20 to force this member axially on its arbor 19 a slight but predetermined distance. To effect this impact adjustment of the lap 20 a bracket 21 is mounted upon the base of the machine having a plunger 22 therein disposed accurately in alignment with the spindle 10 and arbor 19. This plunger 22 is mounted within the retractable member 23 within the bracket 21 and is normally forced toward the lapping spindle by a helical spring 24. By manually retracting this member 23 which compresses the spring 24, then upon release of the member 23 the plunger 22 will be forced forwardly and its end face will be brought into contact with and force the lapping tool 20 axially along its arbor 19. To adjust the axial position of the plunger 22 so that its end face will strike the end of lapping sleeve 20, the plunger 22 may be threaded throughout the major portion of its length, the threads of which engage a retractable detent 25. The plunger 22 may therefore, by rotation, be accurately adjusted so that when forced forward it will strike the lap 20. Also by disengaging the detent 25 the plunger 22 may be quickly moved any distance in either direction. The forward or striking end of this plunger 22 may be provided with an adapter 26 rotatable within the plunger 22 and recessed to fit over the end of the lapping arbor 19 and directly engage the front face of the sleeve forming the lap.

In order to control the blow effected by this plunger 22, means are provided to adjust the pressure of the helical spring 24. As will be seen in Fig. 3, the helical spring is housed in the bracket 21 within a suitable recess. The forward end of the spring 24 bears against the head of a bolt 27 extending through the bracket 21 and through a portion of the retractable member 23. The outer end of this bolt 27 is threaded and is en-

gaged by a suitable manual adjusting nut 28. By rotation of this nut 28 the pressure of the helical spring 24 holding the retractable member 23 in its forward position may be widely varied. In order to control the delivery of the blow of the plunger 22 against the lap 20 a hand lever 29 is provided having a projection or latch 29a adapted to engage a depending portion of the retractable member 23 so that by oscillation of this handle 29 the projection will be disengaged from the depending portion of the retractable member 23 after a predetermined movement. This will release the retractable member 23 for forward movement under the pressure of the helical spring 24. To adjust the plunger 22 so that it will contact the end face of the lapping tool and advance this tool a predetermined distance when released it is only necessary to rotate the plunger 22 within the retractable member 23.

The particular and preferred means to retain the work piece W while being operated on is shown most clearly in Figs. 5 and 6. It will be seen that the member actuating this holder 30 is in the form of a bracket 31 having a bar or rod 44 adjustably fixed thereto, the bar 44 being reciprocated by means presently to be described.

This bracket member 31 has a transverse horizontal hole therein engaged by a cylindrical projection 32 on the work piece holding member 30 so that this holder may oscillate about the axis of this projection. Extending laterally from member 39 are notched arms 33 extending above and below the axis of the lapping tool 20 so that projections 35 on the work piece clamping member 34 may engage the notches and be retained therein by a swivel member 36 having arms fitting against the projections on the work piece clamping member. Preferably, spring means 37 are provided for normally retaining the swivelling member 36 in its work piece retaining position, the tension being adjustable by rotation of one end of a helical spring, the opposite end of which is attached to the shaft or spindle 38 on which this swivelling member 36 is rotatably supported. Also a lever or arm 39 may be provided permitting manual disengagement or oscillation of this member so that the clamping member 35 and work piece W may be conveniently placed in or withdrawn from the holder 30. By means of the swivelling member 36 being spring held in position to engage oppositely extending arms on the work clamping member 35 when the traversing movement of the work piece W along the lap 20 is reversed, the drag of the lap 20 over the work piece W will force the projections 35 to the opposite sides of the notches in projections 33 causing the swivelling member to swing an amount dependent upon the drag when the movement of the holder 30 is toward the spindle 10. By watching the swivelling action of this member 36 the amount of lapping action can be determined and when movement of the swivelling member does not occur it indicates that no lapping is being effected. To hold the work piece, which in the form of the invention shown in the drawing is a small threaded roll, the clamping member 34 surrounds and is in clamping engagement with its outer periphery. From the top and bottom of this clamping member 34 extend the radial arms carrying the projections 35 which engage within the notches in the holding and reciprocating member 30.

In operation the spindle 10 carrying the lap 20 is rotated at any desired speed; if desired, the spindle may be rotated a few revolutions in each

direction but may be rotated continuously in one direction without losing the advantages of the present invention. By periodically reversing rotation of this spindle lapping will take place equally during rotating in either direction of rotation, these reversals of rotation also providing for an even distribution of the lapping compound. The lapping operation, therefore, is speeded and rendered more uniform from end to end of the work piece. During this rotation of the spindle 10 the work holding member 30 is reciprocated through variable distances regulated by the adjustable stops 40 on the valve shaft 41 directly above the operating piston 42. As any standard type of mechanism may be employed for these reciprocatory movements, no further description of them is thought to be necessary other than to say that the piston 42 is moved hydraulically within a cylinder 43 and reciprocates the member 30 and the rod 44 attached thereto between limits determined by the position of stops 40.

What I claim is:

1. In a lapping machine, a holder comprising a clamping member engaging a work piece, co-axial alined projections extending from opposite portions of said clamping member, a yoke member having recesses engaging said projections whereby said work piece may swivel about the axis of said projections, and a projection on said yoke member extending at right angles to the axis of said recesses whereby said work piece may be reciprocated by means engaging said last named projection.

2. In a lapping machine, a holder comprising a clamping member engaging a work piece, co-axial alined projections extending from opposite portions of said clamping member, a yoke member having recesses engaging said projections whereby said work piece may swivel about the axis of said projections, and a projection on said yoke member extending at right angles to the axis of said recesses about which said yoke member may swivel whereby said work piece may be reciprocated by means engaging said last named projection while being free to adjust itself about axes normal to each other.

3. In a lapping machine, a holder comprising a clamping member engaging a work piece, co-axial alined projections extending from opposite portions of said clamping member, a yoke member having recesses engaging said projections whereby said work piece may swivel about the axis of said projections, means to retain said projections within said recesses, and a projection on said yoke member extending at right angles to the axis of said recesses about which said yoke

member may swivel whereby said work piece may be reciprocated by means engaging said last named projection while being free to adjust itself about axes normal to each other.

- 5 4. In a lapping machine, a holder comprising a clamping member engaging a work piece, co-axial alined projections extending from opposite portions of said clamping member, a yoke member having recesses engaging said projections whereby said work piece may swivel about the axis of said projections, means to retain said projections within said recesses, and a projection on said yoke member extending at right angles to the axis of said recesses, and a reciprocating member rotatably engaging said last named projection whereby said work piece may be reciprocated by means engaging said last named projection.
- 10 5. A lapping machine comprising in combination, a base having a lapping tool rotatable therein, a piston reciprocable in a direction parallel to the axis of rotation of said lapping tool, a holder comprising a clamping member engaging a work piece on said lapping tool, co-axial alined projections extending from opposite portions of said clamping member, a yoke member having recesses engaging said projections whereby said work piece may swivel about the axis of said projections, and a projection on said yoke member extending at right angles to the axis of said recesses whereby said work piece may be reciprocated over said lapping tool by said piston.
- 15 6. In a lapping machine, a work holder comprising a clamping member engaging a work piece, a yoke member mounting said clamping member for free adjustment about an axis normal to the axis of the work piece being lapped, said yoke member being mounted for free adjustment about an axis normal to the axis of adjustment of the clamping member and the axis of the work piece being lapped, and means to reciprocate the work piece, clamping member and yoke member axially over a lapping tool.
